(57) **CLAIM**

The ornamental design for a curved label holder, as shown
and described.

DESCRIPTION

FIG. 1 is a perspective view of a curved label holder
showing my new design;

FIG. 2 is a left side elevational view thereof, with a right side
elevational view being a mirror image thereof;

FIG. 3 is a front elevational view thereof;

FIG. 4 is a rear elevational view thereof; and,

FIG. 5 is a top plan view thereof, with a bottom plan view
being a mirror image thereof.
